UNITED STATES PATENT OFFICE.

ERNEST REICH, OF CHICAGO, ILLINOIS.

DESIGN FOR A DISPLAY BOOTH.

Application filed February 17, 1928. Serial No. 25,478. Term of patent 14 years.

To all whom it may concern:

Be it known that I, ERNEST REICH, a citizen of the United States of America, residing at Chicago, in the county of Cook and State of Illinois, have invented a new, original, and ornamental Design for Display Booths, of which the following is a specification, reference being had to the accompanying drawing, forming part thereof, the opposite sides of the device being similar in contour and ornamentation to the sides shown in Figures 1 and 2.

Fig. 1 is a front view of a display booth, showing my new design.

Fig. 2 is a side view.

I claim:

The ornamental design for a display booth, as shown and described.

In witness whereof I affix my signature.

ERNEST REICH.
